UNITED STATES PATENT OFFICE

ALEXANDER G. BARRETT, OF IDABEL, OKLAHOMA

DANCING DOLL

Application filed May 8, 1930. Serial No. 450,813.

The present invention relates to dancing dolls or toys.

An object of this invention is to provide a dancing doll which is so constructed that it may be set in motion by any desired power means, being adapted for attachment to a phonograph or other rotating member and also so constructed that it may be readily mounted on the radiator or other part of a motor vehicle.

Another object of this invention is to provide means by which a number of dolls may be mounted upon a single supporting structure and so positioned thereupon as to dance in unison.

The above and various other objects and advantages of this invention will in part be described in and in part be understood from the following detailed description of the present preferred embodiment, the same being illustrated in the accompanying drawing wherein:

Figure 1 is a detail side elevation partly in section of a device constructed according to the preferred embodiment of this invention;

Figure 2 is a sectional view taken on the line 2—2 of Figure 1; and

Figure 3 is a sectional view of the device taken on the line 3—3 of Figure 1.

Referring to the drawing wherein like numerals of reference designate corresponding parts throughout the several views, the numeral 10 designates a base upon which are mounted vertically disposed supporting members 11 and 12, the supporting member 11 being positioned at the front or forward end of the device and the supporting member 12 being positioned at the rear thereof. The support 11 is provided at the upper end portion thereof with an aperture 13 therethrough and in like manner the supporting member 12 is provided with an aperture 14 therethrough which aligns with the aperture 13 in the front support so as to rotatably receive a horizontally disposed shaft 15.

A power member 16 is secured to one end of the shaft 15 and in the preferred embodiment of this invention the power member is disclosed as being constructed in the form of a propeller or the like which is adapted to be

rotated by contact with wind or the like, the base 10 being preferably mounted in the wind such as on a motor vehicle or, if desired, the base 10 may be mounted on a stationary supporting post which is in a draft of air or the like.

While I have disclosed the power member 16 as being constructed in the form of a propeller I do not wish to be limited to this construction as, if desired, a grooved pulley or the like may be mounted on one end of the shaft 15, and the pulley connected by means of a flexible band or the like to any other desired power member as a phonograph, an electric motor or the like.

The drive shaft 15 is provided intermediate the ends thereof with a reduced shaft 17, the drive shaft being cut away at 18 and a dancing doll or other member generally designated as 19 is adapted to be mounted upon the offset crank portion 17. The doll or figure member 19 comprises a body or torso portion 20 upon which is mounted a head 21, and a pair of legs 22 are pivotally secured to the lower end portion of the torso 20 and, if desired, feet members 23 may be pivotally secured to the lower end portions of the leg members 22.

The body 20 is provided intermediate the upper and lower end portions thereof with a horizontally disposed aperture therethrough 24 which preferably is of flaring construction adjacent the outer end portions thereof, the aperture 24 being adapted to rotatably receive the crank portion 17 of the drive shaft 15. The drive shaft 15 is provided with an eccentrically disposed member 25 which extends inwardly from the cut out portion 18 and is adapted to strike the body or torso 20, the eccentric portion 25 being preferably constructed in such a manner that it will impart a rocking or forward and rearward movement to the torso 20 upon rotation of the shaft 15. This forward and rearward movement of the body 20 is adapted to substantially simulate the swaying movement of a dancing doll and this movement is imparted simultaneously with the raising and lowering of the doll by means of the offset crank portion 17.

The rear supporting member 12 is provided with an upwardly extending elongated slot 26 for receiving a fin or rearwardly extending vane member 27 which is of sufficient size so as to hold the propeller or power member 16 into the wind, it of course being understood that if desired the base 10 may be rotatably mounted on a desired supporting member in which case the fin 27 will maintain the propeller or power member 16 in engagement with the wind so that it will be rotated thereby.

Where the device is used in conjunction with other power means than the propeller 16 the fin 27 may be dispensed with. While I have shown the shaft 15 as being provided with only one offset crank 17 for receiving a single doll member 19 I do not wish to be limited to this construction as the shaft 15 may be provided with any number of crank members 17 therealong for receiving any number of dancing doll members 19.

In the operation of this device, the base 10 together with the vertically disposed supports 12 may be mounted in any desired position and preferably mounted where a considerable draft of air will strike the propeller or power member 16. Upon rotation of the power member 16 the shaft 15 will be coaxially rotated and the rotation of the shaft 15 will impart a vertical movement to the doll member 19 so that the feet of the doll will be constantly striking the base 10 and due to the hinged construction of the leg members 22, the feet will be constantly moving coaxially with the vertical movement of the body 19.

When the shaft 15 is rotated, the eccentrically disposed portion 25 will strike the outer surface of the body 19 and impart a forward and rearward rocking movement thereto, this movement being readily permitted by the tapering construction of the outer end portions of the aperture 24 through the body. It is of course understood that the body 19 is provided with suitable swinging arm members 28 which will swing coaxially with the swaying movement of the body.

It will be obvious from the foregoing that an amusing toy has been disclosed which may be very cheaply manufactured and which may be operated by various power members and, if desired, used for display purposes in show windows or the like.

It will, of course, be understood that various changes and modifications may be made in the details of construction and design of the above specifically described embodiment of the invention without departing from the spirit thereof, such changes being restricted only by the scope of the following claims.

What is claimed is:

1. A dancing figure toy of the character described, said dancing figure toy having a horizontally disposed aperture, said aperture being flared at the opposite end portions

thereof, a shaft, an offset crank on said shaft intermediate the ends thereof loosely mounted in said aperture of said body portion, an eccentric secured to said shaft, said eccentric engaging the flared portions of the body whereby to impart a swaying motion to the body, and leg members depending from said body and adapted for intermittent engagement with a base.

2. A dancing figure toy of the character described, comprising a body having a horizontally disposed aperture, said aperture being flared at the offset end portions thereof, a shaft, an offset crank secured to said shaft intermediate the ends thereof, a propeller secured to one end of said shaft, said propeller being adapted to be rotated in a draft of air, a pair of vertically disposed supporting members, means carried by the shaft and engaging said body whereby to impart a swaying motion to the body cooperatively with the vertical movement thereof, and a rearwardly extending fin secured to one of said supporting members, said fin being adapted to keep the dancing figure toy facing the draft of air.

3. A toy of the character described comprising a drive shaft, means for rotatably supporting said shaft, an offset crank secured to said drive shaft, a figure having a horizontally disposed aperture therethrough loosely mounted on said offset crank, an eccentric secured to said drive shaft and engaging said figure whereby to impart a swaying motion to the figure simultaneously with the rocking motion imparted by the offset crank.

In testimony whereof I hereunto affix my signature.

ALEXENDER G. BARRETT.
